Primary Examiner — Kimberly Barnes(74) *Attorney, Agent, or Firm* — NORTON ROSE FULBRIGHT CANADA(57) **CLAIM**

The ornamental design for a hockey goalie mask as shown and described.

DESCRIPTION

FIG. 1 is front side perspective view of a hockey goalie mask showing our new design;

FIG. 2 is a rear side perspective view thereof;

FIG. 3 is a front elevation view thereof;

FIG. 4 is a right side elevational view thereof, the left side elevational view being a mirror image of FIG. 4;

FIG. 5 is a top plan view thereof; and,

FIG. 6 is a rear elevation view thereof.

The broken line portions show portions of the hockey goalie mask that do not form part of the claimed design.

1 Claim, 6 Drawing Sheets(56)
